L. BRÉGUET ET AL
APPARATUS TO CONTROL THE NUMBER OF TURNS OF THE DRAWING SHAFT
IN DRAWING BENCHES
Filed Dec. 11, 1923

UNITED STATES PATENT OFFICE.

LOUIS BRÉGUET AND PAUL BRÉGUET, OF GENEVA, SWITZERLAND.

APPARATUS TO CONTROL THE NUMBER OF TURNS OF THE DRAWING SHAFT IN DRAWING BENCHES.

Application filed December 11, 1923. Serial No. 680,047.

To all whom it may concern:

Be it known that we, LOUIS BRÉGUET and PAUL BRÉGUET, citizens of Switzerland, residing at Geneva, 74 Rue de Carouge, Switzerland, have invented certain new and useful Improvements in Apparatus to Control the Number of Turns of the Drawing Shaft in Drawing Benches, of which the following is a specification.

- 10 The present invention relates to mechanism for controlling the rotation of the drawing shafts of wire-drawing apparatus; the term "drawing shaft," as herein used, being intended to indicate the shaft of the drawing bench which drives the spools, pulleys or other elements employed to effect the movement of the wire. If only one spool is utilized, the drawing shaft may be the shaft whereon such spool is mounted.
- 15 It is well known to those skilled in the art that the drawing of the wire, or its winding, becomes more and more difficult as the diameter of the wire decreases and the drawing velocity increases. The slightest variation in expansion may cause rupture of the wire, which may entail considerable loss of time, particularly in the case of machines for manufacturing very fine wire; the rupture of the wire also impairing its quality.
- 20 The object of this invention is to provide, especially in fine wire manufacturing, a means or mechanism for automatically controlling the velocity of the drawing shaft so as to constantly maintain the stress exerted on the wire as nearly as possible at a predetermined normal degree.

An embodiment of the invention is illustrated in the accompanying drawing, in which Figure 1 is a perspective view of the improved controlling mechanism, and Fig. 2 is an enlarged view, in front elevation, of a detail.

Referring more particularly thereto, *a* indicates the drawing shaft and *c* a cone pulley on said shaft which is driven by a belt *b*, assumed to travel at a constant speed; the position of the belt on the cone being adjusted by means of a shifting fork *n*¹, operated as hereinafter described. Shaft *a* carries the drawing spool *d* on which the wire *e*

is threaded after having been led over a swinging or vibrating roller *f*, the latter being mounted on the lower end of a rod *f*¹ which extends downward from a horizontal shaft or spindle *f*² suitably journaled and supported in the framework; the arrangement being such, therefore, that the parts *f*¹ and *f* conjointly form a pendulum whose axis of oscillation is the shaft *f*².

The shaft *f*² has secured to it a lateral arm *g* carrying an adjustable counterweight *g*¹ which tends to rock said shaft in an anti-clockwise direction, with a resultant outward or rightward movement or swing of the pendulum; the position of the weight *g*¹ determining the amplitude of the swing. The end of the shaft remote from that to which the pendulum is affixed has secured to it a semi-circular cam *f*³, designed to automatically control the rotation in either direction of a horizontal rock shaft *l* having a threaded portion whereon is mounted a traveling nut or collar *n* carrying the shifting fork *n*¹. Hence, the axial movement of collar *n* in one direction or the other along shaft *l* will produce a corresponding movement of the belt toward one or the other end of the cone *c* and, consequently, a change in the speed of the drawing shaft *a*.

The cam *f*³ forms part of the controlling mechanism wherein our invention primarily resides. As shown in Fig. 2 the flat underfaces of the two horns of the cam rest upon the up-turned inner ends of a pair of pawls *h*¹, *h*² which are centrally mounted upon pivot bolts *h*⁷ carried by lugs or projections *h*⁸ formed on the free end of the upper arm *i* of a bell-crank rocker loosely mounted at its apex on the rock-shaft *l*. The lower or horizontal arm *i*¹ of the rocker is connected by a rod *m*¹ with an eccentric *m* which is continuously rotated in any desired manner, so that the rocker will thus be subjected to a constant swinging movement, as will be understood. The outer portions or tails of the pawls are connected by retractile springs *s* with the corresponding parts of a second pair of pawls *h*³, *h*⁴ which are mounted on bolts *h*⁹ carried by the rocker arm *i*, and the inner ends of these pawls *h*³, *h*⁴ engage the

upper ends of a third pair of pawls h^5 , h^6 , mounted on pivot bolts h^{10} fixed to arm i ; the lower arms of the third pair being connected by a retractile spring s^2 . The last-
5 named pawls have the free ends of their lower arms designed for coaction with a pair of ratchet wheels k^1 and k^2 , the teeth of which are inclined in opposite directions; said wheels being keyed to the rock-shaft l
10 so as to impart a rocking movement thereto in one direction or the other, according as one ratchet or the other is positively rotated.

The mechanism just described acts, therefore, in much the same way as a pendulum-controlled driving device or escapement; that is to say, when the tension of the wire upon the roller f or pendulum weight exceeds a predetermined normal—which is the tension for which the mechanism has originally
15 been set by the adjustment of weight g^1 —the pendulum will be forced inward and will produce a clockwise rotation of shaft f^2 ; and when the tension falls below such normal, the pendulum swings outward and
20 rotates shaft f^2 anti-clockwise. In both cases, the rotation of said shaft entails a lateral movement of the shifting fork n — n^1 to one side or the other on shaft l and a resultant movement of the driving belt along
25 cone c ; the movement of the fork being caused by the rotation of shaft l which is produced by the operation of the escapement. If the tension of the wire coincides with the aforesaid predetermined normal,
30 then the pendulum or controller will remain stationary, and the escapement will not be actuated.

In the first of the three cases mentioned, the clockwise rocking movement of the controller shaft f^2 will produce a similar movement of the cam f^3 thereon, and the right-hand horn of said cam will depress the inner arm of the adjacent pawl h^2 ; the latter, through its spring connection s , rocking
45 pawl h^4 anti-clockwise and, in consequence, causing the inner arm of said pawl h^4 to act, in turn, upon pawl h^6 to disengage it from ratchet k^2 . Through the same movement of cam f^3 , coupled with the action of the
50 springs s , s^2 , the left-hand pawl h^5 is engaged with ratchet k^1 and, during the succeeding movement of the rocker, turns shaft l anti-clockwise, thereby producing a left-hand movement of the shifting fork and a movement of belt b toward the larger end
55 of cone c , thus reducing the speed of the drawing shaft.

In the second case, where the tension drops below normal, the reverse operations
60 take place. Pendulum f , f^1 moves outward and produces an anti-clockwise rotation of shaft f^2 and its cam f^3 ; this movement of the cam effecting the disengagement of pawl h^5 from ratchet k^1 and the engagement of
65 pawl h^6 with ratchet k^2 , with the result that

shaft l is rotated clockwise, fork n , n^1 moves rightward thereon, and belt b moves toward the smaller end of cone c and drives shaft a at an increasing speed.

In the third case, where the tension is
70 normal, the pendulum and its connected rock-shaft f^2 remain stationary, the cam f^3 occupies a neutral position in which the under faces of its two horns are horizontal,
75 and the several springs hold both pawls h^5 and h^6 out of engagement with their respective ratchets. Hence the bell-crank rocker will oscillate idly without producing any rotation of shaft l . This pendulum operated escapement is such a sensitive controller
80 of the speed that fine wire manufacturing becomes a good deal less troublesome because less loss by waste will be occasioned and much time saved.

It will be understood that the rocker, the set of pawls thereon, and the eccentric m and its connecting rod m^1 conjointly form an auxiliary driving device or servo-motor which is utilized to effect the automatic shifting of the belt b ; this servo-motor being entirely independent of the drawing shaft so that the power necessary for the belt-shifting operation is no longer required to be taken from said shaft. This means, also, that the wire is relieved from the strain needed to overcome the working of the belt-shifter, that less breaks of wire will occur, and that the use of a servo-motor for operating the change-speed device can hardly be dispensed with in fine wire manufacturing. However, while the preferred form of servo-motor has been illustrated herein, an electric, pneumatic or other type of driving device or motor might be substituted, and the rocker may be operated otherwise than by a pendulum. Other and further modifications and changes might also be made within the scope of the invention.

We claim:—

1. In a wire-drawing bench, the combination of a drawing shaft; a cone pulley thereon; a driving belt passing around the pulley; a belt shifter engaged with said belt to move it toward either end of said pulley; an independent mechanism for moving the belt shifter in either direction; a pendulum controlled by the strain of the wire for starting said mechanism; and a weighted lever for counter-balancing the pendulum.

2. In a wire-drawing bench, the combination of a drawing shaft; a cone pulley thereon; a driving belt passing around the pulley; a belt shifter engaged with said belt to move it toward either end of said pulley; a shaft having a threaded portion whereon said shifter is mounted to travel; a pair of escapement wheels fixed to the second-named shaft to effect right- and left-hand rotation thereof; an angular rocker loosely mounted on said second-named shaft; pawls carried

by said rocker for alternative engagement with said wheels; independent driving means connected to operate said rocker; a third shaft; a two-horned cam fixed to the third shaft to throw out either pawl; and a pendulum forming a feeler arm for the wire to control the position of said cam and

thereby slacken or decrease the speed of the drawing shaft.

In testimony whereof we affix our signatures.

LOUIS BRÉGUET.
PAUL BRÉGUET.
